ATTORNEY

UNITED STATES PATENT OFFICE

GEORGE SUBICK, OF CHICAGO, ILLINOIS

GARMENT HANGER FRAME

Application filed April 5, 1930. Serial No. 441,904.

This invention relates to certain novel improvements in garment hanger frames and has for its principal object the provision of an improved construction of this character which will be highly efficient in use and economical in manufacture.

It is among the objects of my invention to provide a device of the above named character which will be arranged so as to embody two side members which are preferably of a one piece construction and which will preferably have portions thereof joined together by welding.

Another object of the invention is to provide an expeditious arrangement for joining the side frames.

A still further object of the invention is to provide a frame which will embody portions that will support a protecting covering and other portions on which garment hangers of approved form may be arranged.

A still further object of the invention is to provide a construction of the above described character which in a modified form will embody spaced apart supporting members which will be adjustably connected to the side frames in order that they may be spaced apart in predetermined amounts.

Other objects will appear hereinafter.

The invention consists in the novel combination and arrangement of parts to be herein-after described and claimed.

The invention will be best understood by reference to the accompanying drawings, showing the preferred form of construction and in which:

Fig. 1 is a front elevational view of a preferred form of construction with which my invention is intended to be associated;

Fig. 2 is a top plan view of my improved frame construction;

Fig. 3 is an end elevational view thereof;

Fig. 4 is a side elevational view of a modified form of construction;

Fig. 5 is a fragmentary elevational view of the frame illustrated in Fig. 4; and

Fig. 6 is a perspective view of certain parts of the invention.

In the accompanying drawings wherein I have illustrated a preferred form of con-

struction for my invention, 10 and 11 indicate vertically extending supporting standards which are connected at their upper ends to a cross member 12. The supporting standards 10 and 11 include foot portions 13 which serve to support the standards 10 and 11 to prevent displacement thereof. My improved frame is intended to be supported from the cross member 12.

My improved frame is generically indicated by 14 and includes side members 15 and 16. By referring to Fig. 3 it may be seen that the side frame 16 includes an upper rail 17. One end of the upper rail 17 terminates in a looped portion 18 which looped portion 18 terminates in a downwardly extending portion 19. The portion 19 extends at an acute angle with respect to the extent of the portion 17. The other end of the portion 17 terminates in a looped portion 20 which looped portion 20 in turn terminates in a portion 21 which extends downwardly at an acute angle with respect to the portion 17. The portions 19 and 21 are connected to the lower end of a center brace member 22 which is also connected to substantially the midpoint of the extent of the portion 17. These various portions may be defined by stamping the side frame 16 from a single piece of material or the side frame 16 may be formed from suitably shaped sections which will have the ends thereof suitably joined together as by welding.

Secured to the section 17 and extending upwardly therefrom in alignment with the center brace 22 is a hook 23. The side frame 15 is constructed in a manner substantially similar to that set forth.

By referring to Fig. 3 it may be seen that the center brace is arranged to extend vertically and the hook 23 is associated therewith so as to facilitate this. The section 17 is arranged to extend angularly with respect to the horizontal and is preferably arranged so that the end embodying the loop portion 18 is arranged at a lower horizontal level than the end embodying the looped portion 20. This arrangement is such that when the hooks or garment hangers are disposed on the rod 30 these hooks may be

easily located since the front ends of the side frames 15 and 16, facing the opening 33 in the drape 32, will be disposed higher than the other end of these frames 15 and 16 so 5 that supporting rod 30 may be readily seen and the garment hanger hooks readily removed from the rod 30 by the operator entering his arms through the slit 33, without the necessity of pushing other garment hangers and the garments thereon from side to side to find the particular garment hanger on the rod 30 that it may be desired to remove from rod 30. The portion 15 is similarly arranged and this arrangement permits the 15 protective sack 32 to be draped over and conveniently and detachably secured to the device in the manner to be explained herein-after.

In order to join the side frames 15 and 20 16 together I provide rod members 24, 25, and 26. In the ends of the rod member 24 are tapped openings and bolt members 27 are extended through the looped portions 20 of the frames 15 and 16 and are threaded 25 into these tapped openings. In a similar manner bolt members 28 are threaded into the ends of the rods 26 and the bolt members 28 are extended through the looped portions 18. Openings are provided in the center braces 30 22 through which bolt members 29 are extended which are also extended into tapped openings in the end of the cross brace 25. This extension of the bolt members into 35 tapped openings in the ends of the rod members serves to very effectively join the side frames 15 and 16 together. If desired the rod members 24 and 25 and 26 may be made from tubular material which will facilitate the tapping of the openings in the ends 40 thereof.

A supporting bar 30 extends between the center braces 22 adjacent the lower end thereof and if desired this supporting bar 30 may be made from tubular material. The supporting 45 bar 30 is arranged to embody tapped openings in the ends thereof and bolt members 31 are extended through openings in the center braces 22 and are threaded into these tapped openings and thus the supporting bar 50 30 is very effectively supported.

After the side frames 15 and 16 have been joined together in the manner set forth the hooks 23 are disposed on the horizontal supporting bar 12 and it is, therefore, manifest 55 that the frame 14 will be supported from this bar 12. Prior to the time the hooks 23 are associated with the supporting bar 12 I arrange the sack 32 on the supporting frame 14. This sack 32 is preferably made from a 60 suitable dust-proof textile material and has a slit in one face thereof indicated by 33 which may be opened in order that clothing or the like supported on suitable hangers may be inserted into this sack 32 and the hangers having 65 the clothing associated therewith will be

suspended from the bar 30. The particular arrangement of the textile sack 32 and the manner in which the clothing is associated therewith is particularly described and claimed in my U. S. Patent No. 1,773,888, 70 dated August 26, 1930, which patent relates to improvements in storage chambers.

In Figs. 4 and 5 I have illustrated a slightly modified form of construction of the side frames. In this instance the side frames are 75 each preferably formed from a single elongated strip of material, such as a length of wire or the like. In forming the side frame the wire is bent centrally upon itself and the wire portions adjacent the bight portion 34 are turned or twisted so as to wind the wire portions upon themselves to provide a hook portion 35. Intermediate the bight portion 34 the portions of the wire member are buckled outwardly as at 36 to provide an opening 37 for the passage of the screws 29 and below this opening the wire members are again twisted or wound together as at 38. Below the twisted portion 38 the portions of the wire member are looped to provide an 80 opening 39 for the passage of the screw 31. Adjacent portions of the wire member are then bent to be disposed at an inclination with respect to each other and extend upwardly in opposite directions where intermediate portions are again looped to provide 85 openings 40 for the passage of the screws 27. The end portions are then bent toward each other in a substantial horizontal plane with their extremities looped about the lower portion 41 of the hook 35 above the portions 36 providing the opening 37 thus completing 90 the side frame member which is formed as indicated from a continuous strip of material. 95

I have found that by forming each of the 100 frame members from a single length of wire that the cost of production is greatly reduced and that the same is more economical in use.

After the formation of each side frame member from the single length of wire the 110 same may be coated with a suitable chemical to prevent rust or the like.

While I have illustrated and described the preferred form of construction for carrying 115 my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. A frame of the character stated including side plates comprising arms arranged to provide loop portions at the ends thereof, said side plates having central portions therein, bars extended between said side plates, and 130

- a supporting member extended between said center portions, bolt members extended through said loop portions and openings in said central portions and into tapped openings in the ends of said bars whereby to interconnect said bars to said side plates, said side plates having the center portions thereof arranged to extend in a vertical plane and having the upper edges thereof arranged at an angle with respect to the horizontal whereby one end thereof will be disposed in a lower horizontal plane than the other end thereof whereby when said frames are supported and garment hangers are suspended by their hooks from said supporting member said hangers and hooks may be readily seen and located without having to move other garment hangers from side to side to find the one desired.
2. In a supporting device for garment hangers, a pair of spaced apart side frames each including rails integrally formed with each other and forming in outline substantially an isosceles triangle, a brace member extending between the apex and base of each of said triangular frames, rod members extended between said frames at the ends of said bases, a bar extending between said braces adjacent said apexes and from which garment hangers may be suspended, and a hook element on each of said braces at the end thereof opposite the apex of each of said triangular side frames and said hooks being adapted to suspend the device from a suitable support.
3. In a supporting device for garment hangers, a pair of spaced apart side frames each including rails integrally formed with each other and forming in outline substantially an isosceles triangle, a brace member extending between the apex and the base of each of said triangular frames, and the ends of said base rails each terminating in a loop, tubular members extended between said frames and said loops, a bar extending between said braces adjacent said apexes and from which garment hangers may be suspended, a hook element on each of said braces at the end thereof opposite the apex of each of said triangular side frames and said hooks being adapted to suspend the device from a suitable support, and connecting elements inserted through said loops and into the ends of said tubular members for securing said tubular members to said frames.
4. In a supporting device for garment hangers, a pair of spaced apart side frames each having one end higher than the other when the device is supported above a surface, brace members at the central portions of said frames, rod members extended between said frames at the ends thereof, a supporting bar extending between said braces and from which garment hangers may be suspended, a hook element on each of said braces at the top thereof and said hooks being adapted to suspend the device from a suitable support, so that a particular garment hanger and its hook suspended from said supporting bar may be readily seen and located for removal therefrom.
5. In a supporting device for garment hangers, spaced side frames, adapted to support a fabric cover means for retaining said side frames in spaced relationship, means on said frames for supporting said device from a support, and a supporting member extending between said frames and from which garment hangers may be suspended by their hooks, said frames being so formed that one end of each of said frames will be higher than the other end when said device is supported by said means so that said hanger hooks may be readily seen and located upon said supporting member for removal therefrom.
- In testimony whereof I affix my signature.
- GEORGE SUBICK.
